[57] CLAIM

We claim the ornamental design for a hunting arrow with attached signal-generating device, as shown and described.

DESCRIPTION

FIG. 1 is a front, top and side perspective view of the hunting arrow with attached signal-generating device embodying the design of the present invention;

FIG. 2 is a front elevational view thereof;

FIG. 3 is a rear elevational view thereof;

FIG. 4 is a side elevational view thereof, the opposite side elevational view being identical thereto;

FIG. 5 is a top plan view thereof; and,

FIG. 6 is a bottom plan view thereof.
